(Cl. D49—6)

To all whom it may concern:

Be it known that I, Alec Tucker a British subject residing at Otford, Kent, England, have invented a new, original, and ornamental Design for an Electric Steam Iron, of which the following is a specification, reference being had to the accompanying drawings.

In the drawings:

Figure 1 is a perspective view from the front of an electric steam iron, showing my new design;

Figure 2 is a perspective view from the rear of the iron;

Figure 3 is a top plan view;

Figure 4 is an inverted bottom plan view;

Figure 5 is a front view slightly in perspective of the iron; and

Figure 6 is a side elevation of the iron.

I claim:

The ornamental design for an electric steam iron, substantially as shown.
